Primary Examiner — Jonathan J Han*Assistant Examiner* — Caitlin Mackenzie Williams(74) *Attorney, Agent, or Firm* — Marshall A. Lerner; Steven J. Kim; KLEINBERG & LERNER, LLP**CLAIM**

The ornamental design for a shoe upper, as shown and described.

DESCRIPTION

FIG. 1 is a rear perspective view of a shoe upper in accordance with our new design;

FIG. 2 is a rear view of the shoe upper thereof; and, FIG. 3 is a right side view of the shoe upper thereof; and, FIG. 4 is a top plan view of the shoe upper thereof. The broken lines shown in the drawings represent portions of the shoe that form no part of the claimed design.
